DESIGN FOR A LAMP BASE

Vine B. Miller, 1414 S. Shipley St., Muncie, Ind. 47302

Filed Apr. 13, 1970, Ser. No. 22,419

Term of patent 14 years

Int. Cl. D26—02

U.S. Cl. D48—20

Fig. 1

Fig. 2

FIG. 1 is a perspective view of a lamp base embodying my new design, showing the front, side and top;

FIG. 2 is an elevational view thereof, all four sides of the lamp base being identical.

I claim:

The ornamental design for a lamp base, as shown and described.
